UNITED STATES PATENT OFFICE.

HOMER F. BARBER, OF SALEM, OHIO.

RAILWAY-RAIL JOINT.

No. 812,717.

Specification of Letters Patent.

Patented Feb. 13, 1908.

Application filed October 19, 1906. Serial No. 283,511.

To all whom it may concern:

Be it known that I, HOMER F. BARBER, a citizen of the United States, residing at Salem, in the county of Columbiana and State of Ohio, have invented new and useful Improvements in Railway-Rail Joints, of which the following is a specification.

My invention relates to railway-rail joints; and its primary object is to provide a novel and highly useful device of this character by means of which the meeting ends of two adjacent railway-rails can be united against sagging, one which is comparatively simple of construction and one which can be manufactured and sold at a comparatively low cost.

A further object of the invention is to provide a railway-rail joint wherein the clamps and joint members thereof are so constructed and relatively arranged that the pressure placed thereon by a train moving over the joint will cause the joint members to more firmly embrace the rails.

With the above and other objects in view, the invention consists in the construction, combination, and arrangement of parts hereinafter fully described, claimed, and illustrated in the accompanying drawings, where-

in—

30 Figure 1 is a view in side elevation of the meeting ends of two railway-rails united by a joint constructed in accordance with my invention. Fig. 2 is a sectional view on the line 2 2 of Fig. 1, and Fig. 3 is a detail perspective view of one of the clamp members.

Referring to the drawings by reference-numerals, 1 designates the bases, 2 the webs, and 3 the treads, of two railway-rails, the same being of the usual form and construction and supported by means of ties 4.

5 designates two joint members or chairs, each comprising a vertically-disposed web-engaging flange 6, a horizontally-disposed base-engaging flange 7, and an underlying flange 8, said flange 8 being spaced from the flange 7, whereby to engage the under surface of the bases of the rails. The joint members or chairs 5 are secured in applied position by means of bolts 9 and nuts 10, the same passing through the flanges 6 and the webs of the rails. The flanges 6 are of a height slightly greater than the distance between the treads 3 and bases 1 of the rails and are bowed outwardly or laterally from the webs 2 thereof, as is fully illustrated in Fig. 2 of the draw-

ings. In the application of the fastening means it is apparent that the bowed portions of the flanges 6 will be caused to move toward the webs 2 of the rails, and thereby bring the upper longitudinal edges of the flanges 6 into forcible engagement with the under sides of the treads 3 and force the flanges 7 down tightly upon the bases 1. To add further to the strength of the joint, I secure to the joint members or chairs three clamps, 65 one being arranged at its longitudinal center and one at each of its ends, said clamps comprising members. The members of the clamps comprise a body portion, from which project upwardly and downwardly curved 70 lips 12, said lips engaging over the outer longitudinal edges of the joint members or chairs, as is fully illustrated in Fig. 2 of the drawings. The body portions of the members 11 are increased in thickness at points 75 adjacent their inner opposing ends and have their inner opposing ends inclined upwardly in reverse directions, as at 13, Figs. 2 and 3, whereby the weight placed upon the joint by a moving train is taken by the clamps and 80 carried toward its transverse center, thus causing the inner opposing ends of the member 11 to approach each other and thus more firmly embrace the joint members. The members 11 of the clamps are secured in applied position by bolts 14 and nuts 15, the bolts extending longitudinally of and fully embedded in the bodies of said members.

The weight placed upon the rail-joint by moving trains will also cause, through the position of the flanges 8, the flanges 6 and 7 to more firmly embrace the rails; and in view of this variable engagement of the rails by the joint members and of the joint members by the clamps it is apparent that I provide a 95 rail-joint which instead of having a tendency to weaken under the weight placed thereon has a tendency to become stronger and to more firmly unite the meeting ends of the rails.

From the foregoing description, taken in connection with the accompanying drawings, the construction and mode of operation of the invention will be understood without a further extended description.

Changes in the form, proportions, and minor details of construction may be made within the scope of the invention without departing from the spirit or sacrificing any of the advantages thereof.

Having fully described and illustrated my invention, what I claim is—

1. In a device of the character described, the combination of the meeting ends of two railway - rails, joint members, and a clamp comprising members, each having its inner opposing end inclined upwardly in a reverse direction.
2. In a device of the character described, the combination of the meeting ends of two railway - rails, joint members having their

vertically-disposed portions bowed, and clamps comprising members, each having its inner opposing end inclined upwardly in a reverse direction, substantially as shown and 15 described.

In testimony whereof I affix my signature in presence of two witnesses.

HOMER F. BARBER.
